Term of patent 14 years

Int. Cl. D14—03
U.S. Cl. D26—14

FIG. 1 is a perspective front view of a telephone cover with handset retainer or the like showing my new design;

FIG. 2 is a perspective front view of a modified embodiment of the design illustrated in FIG. 1; and

FIG. 3 is a rear perspective thereof.

The broken lines are shown for illustrative purposes only and do not form part of the design.

This is a continuation-in-part of design application Ser. No. D. 3,411, filed Aug. 10, 1966, and now Pat. No. D. 212,804.

I claim:

The ornamental design of a telephone cover with handset retainer or the like, as shown and described.
